UNITED STATES PATENT OFFICE.

ALBERT WERNER, OF NEW YORK, N. Y., ASSIGNOR TO WERNER BROS., OF NEW YORK, N. Y., A FIRM COMPOSED OF A. MORTON WERNER, GERSON WERNER, PERETZ WERNER, AND ALBERT WERNER.

DESIGN FOR A FINGER RING.

Application filed January 18, 1923. Serial No. 4,924. Term of patent 3½ years.

To all whom it may concern:

Be it known that I, ALBERT WERNER, a citizen of the United States, residing at New York, in the county of New York and State of New York, have invented a new, original, and ornamental Design for Finger Rings, of which the following is a specification, reference being had to the accompanying drawing, forming part thereof.

The figure is a side elevational view of a finger ring embodying my invention.

I claim:

The ornamental design for a finger ring, as shown.

ALBERT WERNER.
